Int. Cl. D12—09, 14, 99

U.S. Cl. D14—3

FIG. 1

FIG. 3

FIG. 1 is a front perspective view of an auxiliary cab for a pickup truck showing my new design;

FIG. 2 is a front perspective view thereof; and

FIG. 3 is a rear elevational view thereof.

The truck shown in broken lines in FIGS. 1 and 3 is included for illustrative purposes only, and the opposite side of the auxiliary cab is a mirror image of FIG. 2.

I claim:

The ornamental design for an auxiliary cab for pickup truck, as shown and described.
